UNITED STATES PATENT OFFICE

EDWARD H. LORENZ, OF WEST HARTFORD, CONNECTICUT, ASSIGNOR TO HARTFORD-EMPIRE COMPANY, OF HARTFORD, CONNECTICUT, A CORPORATION OF DELAWARE

STARTER FOR MECHANICALLY-DRIVEN MACHINES

Application filed March 28, 1928. Serial No. 265,278.

This invention relates to a method and apparatus for starting a machine which is normally positively driven by constantly running mechanical means and comprises the use of auxiliary means, such for example, as 5 pneumatic pressure or other means starting from rest tending to relieve the shock and load on the driving parts in starting. The invention is especially applicable to machines where the starting inertia is relatively 10 high.

I have chosen to illustrate my invention by its application to a glass blowing machine, such as is shown in my copending application, Serial No. 490,567, filed Aug. 8, 15 1921, which machine is preferably driven in synchronism with a glass feeding means which operates continuously. It becomes necessary or desirable at certain times to 20 stop the operation of a bottle forming machine, while continuing the operation of a glass feeder so as to prevent molten glass from freezing in the feeder opening, or other harmful conditions. When the forming machine is again started up, it must be started 25 in synchronism with the feeder in order to operate properly, and for this reason, a single tooth clutch is ordinarily used connecting the drive shafts of these two machines. The 30 starting torque of machines of this kind is relatively high due to the inertia of the various heavy parts, which are necessary because of the large amount of power necessary to give the turret its intermittent movement, 35 and also due to the power necessary to actuate various other intermittently and continuously moving parts. In the operation of machines of this kind, without my improved device forming the subject matter of 40 this invention, there was a great strain on the driving mechanism which tended to break some of the parts and trip an overload release, which was usually provided, this condition necessitating certain parts being made 45 much stronger than would otherwise be necessary with the consequent increase in cost.

Among the objects of the present invention, therefore, are to provide a device which 50 operates substantially in synchronism with

the clutch engaging members of a machine for overcoming the initial inertia of the parts and setting the machine in motion at or near its full running speed prior to the positive engagement of the regular mechanical driving means. I have found that it is advantageous to accomplish this result by the use of auxiliary and preferably resilient means, 55 as pneumatic pressure, which provides a cushion to relieve the shocks on the machine, and which is effective to overcome the initial load.

A further object of the invention is to provide for the use of resilient means, such as 60 the pneumatic pressure referred to above for starting the machine in predetermined timed relation with the engagement of the positive driving mechanism, such as the clutch above described, so that the pneumatic means will be operated to start the machine just prior 65 to the engagement of the positive mechanical driving means and that when the pneumatic means have moved the machine parts a certain amount, the mechanical means will take 70 up and continue the drive without any appreciable shock or lag.

A further object of the invention is to provide a means associated with a machine of the above described character for starting it by a single manual movement, preferably by 75 the use of a single manual operated valve for engaging the clutch of the positive driving mechanism, and also for actuating the pneumatic starting means.

A further object of the invention is to 80 provide means for resetting the pneumatic starting mechanism in position to start the machine, this operation taking place during the time the positive mechanical drive is disengaged, and preferably comprises a manual 85 resetting means. It is found that in the operation of machines of this type, the starting inertia is different at different parts of the cycle and the present resetting mechanism is so designed that the machine must be reset 90 at the point in the cycle where the starting inertia is least before it can be started automatically.

Further objects and advantages of the invention will be apparent from a reading of 100

the following specification and subjoined claims when taken in connection with the accompanying drawings, in which:

Figure 1 is a fragmentary plan view, partly in horizontal section, of the lower portion and driving mechanism of a bottle forming machine such as is shown in my prior application;

Fig. 2 is an elevation of a part of the driving mechanism with a portion showing the ratchet and pawl device in section on the line 2—2 in Fig. 4;

Fig. 3 is a fragmentary elevation substantially on the line 3—3 in Fig. 1;

Fig. 4 is a section of the drive and pneumatic starting mechanism taken substantially on the line 4—4 in Fig. 1 with certain parts broken away to show the interior construction; and

Fig. 5 is an elevation of a detail partly in section on the line 5—5 in Fig. 2.

The bottle forming machine, in connection with which I have chosen to show my present invention, is mounted upon a base 1 and comprises an intermittently rotated turret generally indicated at 2, and various other mechanisms described in my copending application above referred to. The driving power to actuate various parts of the machine is introduced through a worm wheel 3 (Fig. 1) which is continuously driven and which is provided with a single tooth clutch member or component 4 secured thereto and adapted to be engaged by a cooperating clutch member or component 5 splined to the shaft 6, this shaft constituting one of the main drive shafts of the machine and being operatively connected through gears 7 and 8 to the shaft 9 constituting the other of the main drive shafts. Various of the moving parts of the machine are connected in suitable manner with these two shafts to be operated thereby as set forth in my copending application above referred to.

The clutch component 5 is provided with a collar 10 having a circumferential annular groove in which is received suitable shoes pivoted in the ends of a yoke 11 which is secured to a vertical rock shaft 12 and operated by a horizontally extending lever 13 also secured to shaft 12. A pneumatic cylinder 14 is provided, the piston of which is secured to a rod 15 having its remote end 16 bearing against the lever 13, so that when pressure is admitted to the outer end of the cylinder 14, the rod 15 will be pushed forward against the action of the spring 17 to move the lever 13 in a counter-clockwise direction and engage the clutch components 4 and 5. Pressure may be admitted to the cylinder 14 through a suitable valve 18 controlled by a handle 19. Suitable latch mechanisms, generally indicated at 20, are provided for holding the lever 13 in position to retain the clutch components 4 and 5 in

engagement, as shown in Fig. 1, these mechanisms forming no part of the present invention.

A single tooth ratchet 21 is suitably secured as by a pin 21' on the hub of the turret cam 22 which is in turn secured to the shaft 6. The ratchet 21 is adapted to be engaged by a pawl 23 pivotally mounted at 24 on a disc 25 rotatably mounted on a bearing retainer 26 which is suitably secured as by bolts 27 to the upwardly extending bracket 28 which is integral with or suitably secured to the base 1. Bearing retainer 26 holds in place a fixed outer raceway 29, and ball or roller bearings 30 run in the fixed raceway 29 and an inner raceway 31 secured to the shaft 6. This bearing is of the customary type adapted to carry both radial and thrust loads, permitting easy turning without backlash.

A pneumatic cylinder 32 is suitably formed in or secured to the base 1 adjacent to or integral with the bracket 28, and is provided with a piston 33 and piston rod 34, the latter being connected by a short link 35 with an extended portion 36 of the ring 25, so that upon downward movement of the piston 33, the ring 25 will be turned in a counter-clockwise direction as seen in Fig. 4, turning the shaft 6 through the ratchet 21 and the pawl 23.

A pressure conducting pipe 37 is provided connecting the valve 18 with the upper end of the cylinder 32 above the piston 33 and is so arranged that when pressure is supplied to cylinder 14 by turning the handle 19 of the valve 18, pressure will also be admitted to the cylinder 32 above the piston 33 tending to force it downwardly. The downward movement of the piston 34 is prevented, however, by a latch 38 secured to a rock shaft 39 and having its upper end in engagement with a suitable shoulder 40 on the extended portion 36 of the ring 25.

When it is desired to start the machine, the latch 38 is moved to inoperative position in substantially predetermined time relation with the movement of the clutch components 4 and 5 toward engaging position, this being done by a finger 41 suitably secured, as by bolts 42 (Figs. 2 and 5), to the lever 13, and a lever 43 adapted to cooperate therewith, this lever being secured to the rock shaft 39. A compression spring 44 is employed tending to turn the rock shaft 39 in a counter-clockwise direction, as seen in Fig. 5, to move the latch 38 toward its engaged position. The other end of the lever 43 is provided with an adjustable stop screw 45 adapted to be locked in adjusted position by a jam nut 46, and having its inner end 47 in position to be engaged by the lower end of the finger 41. By adjusting the stop screw 45, the interval between the movement of the latch 38 and the actuation of the pneumatic starting de-

vice on one hand and the positive engagement of the clutch 4-5 on the other may be varied.

From the above description, the operation 5 of the device will be obvious. The handle 19 of the valve 18 is first turned to admit pressure to the cylinder 14 and simultaneously through the pipe 37 to the cylinder 32. The piston 33 is not permitted to move in its cylinder under the action of pneumatic pressure due to the engagement of the latch 38 with the shoulder 40 of the ring 25. The piston in the cylinder 14, however, moves to the right, as seen in Fig. 1, and moves the lever 10 13 in a counter-clockwise direction, thus moving the clutch component 5 toward component 4, the shape of the clutch being such that the components begin to slide together before engagement. However, at a predetermined 15 interval before the components of the clutch are fully engaged, the finger 41 will engage the end 47 of the screw 45 and rotate the rock shaft 39 to disengage the latch 38, thus permitting the pneumatic pressure 20 which is all this time connected with the top of cylinder 32 to move the piston 33 downwardly, thus rotating the ring 25 and the pawl 23 in a counter-clockwise direction, as seen in Fig. 4, and moving the ratchet 21 25 and consequently the cam drum 22 and drive shaft 6 and the other parts of the machine. The pneumatic pressure is designed to bring the machine up to approximately its full operative speed before the positive drive 30 through the clutch 4-5 is effective to sustain the whole driving load, thus starting the machine with little or no shock. Thereafter, the machine is driven in the usual way 35 through the clutch 4-5, as described in my prior application.

Assuming the machine to be stopped and the parts in the position in which they normally are during the operation of the machine, that is after it has been started by the pneumatic means above described, it is necessary 40 to provide means for resetting the ratchet and pawl and the pneumatic piston 33 to the position shown in Fig. 4 before the machine can be again started by these means. For resetting these parts, I preferably employ the means shown in my prior application for adjusting the position of the moving parts of the machine, that is, the hand wheel 48 which may be moved axially to bring a suitable pinion mounted on the other end of its shaft 49 (Fig. 1, the pinion not being shown for the purpose of showing the other parts clearly) into engagement with the gear 55 7. The hand wheel 48 is then turned to move the gear 7 in a direction opposite to that in which it is driven by the mechanical drive and the pneumatic means, so as to rotate the ratchet 21, pawl 23, and ring 25 in a clockwise direction, as seen in Fig. 4, and raise the piston 33 to the upper end of the cylinder

32. When this movement is completed, the hand wheel 48 is then pushed inwardly to a position wherein the pinion on the end of its shaft will be out of engagement with the gear 7 and in an inoperative position, thus placing the parts in readiness for the next starting operation.

While I have shown and described but one embodiment of my invention, and that in its application to a glass forming machine of the type shown in my copending application, it is obvious that many modifications might be made therein and the invention might be applied to many other types of machines without departing from the spirit thereof, as set forth in the appended claims, which are to be construed as broadly as the prior art permits.

I claim:

1. The combination with a mechanically operated machine of a positive mechanical driving means therefor, means to engage and disengage said machine from said driving means, means for applying pneumatically developed power to said machine for starting it just prior to the engagement of said driving means, and means for variably determining the time of operation of said pneumatic means with respect to that of the positive engagement of said driving means.

2. The combination with a machine of positive driving means including a continuously rotating drive member and a positively engaging clutch between said drive member and said machine, of means for applying pneumatically developed power to said machine for starting it, said means adapted to be operated substantially to overcome the starting inertia of the machine before and in timed relation with the engagement of said clutch, and means for varying said timed relation.

3. The combination with a machine of positive driving means including a continuously rotating drive member and a positively engaging clutch between said drive member and said machine, pneumatic means connected to the machine and operable when released substantially to overcome the starting inertia of the machine, and means operable by movement of said clutch toward its engaged position for releasing said pneumatic means to start the machine before and in timed relation with the engagement of said clutch.

4. The combination with a machine of positive driving means including a continuously rotating drive member and a positively engaging clutch between said drive member and said machine, pneumatic means connected to the machine and adapted when released substantially to overcome the starting inertia of the machine, and adjustable means operable by movement of said clutch toward its engaged position for releasing said pneu-

matic means to start the machine before and in timed relation with the engagement of said clutch, whereby said timed relation is variable at will.

5 5. The combination with a machine of positive driving means including a continuously rotating drive member and a positively engaging clutch between said drive member and said machine, means for applying 10 pneumatically developed power to said machine substantially to overcome the starting inertia thereof, a pneumatic cylinder connected to move said clutch into its engaged position, and a single valve to admit pressure to said cylinder to engage the clutch and to said pneumatic power means to start said machine.

6. The combination with a machine of positive driving means including a continuously rotating drive member and a positively engaging clutch between said drive member and said machine, pneumatic means connected to the machine and adapted when released to assist in overcoming the starting 25 inertia of the machine, adjustable means operable mechanically by movement of said clutch toward its engaged position for releasing said pneumatic means to start the machine before and in predetermined timed 30 relation with the engagement of said clutch, a pneumatic means for moving said clutch into its engaged position, and a single valve to admit pressure to said clutch moving means and to said pneumatic means to start 35 said machine.

7. The combination with a machine of positive driving means including a continuously rotating driving member, a driven member operatively connected to various of 40 the moving parts of said machine, a clutch for operatively connecting said members, a ratchet fixed to said driven member, a pawl device adapted to cooperate therewith, and a pneumatic cylinder device connected to and 45 operating said pawl device to move said ratchet to start the machine, said pneumatic cylinder being connected to operate before and in timed relation with the engagement of said clutch.

50 8. The combination with a machine of positive driving means including a continuously rotating driving member, a driven member operatively connected to various of the moving parts of said machine, a clutch 55 for operatively connecting said members, a ratchet fixed to said member, a pawl device adapted to cooperate therewith, a cylinder, a piston in said cylinder operatively connected to said pawl device, means for admitting 60 pneumatic pressure to said cylinder to move said piston in the direction to start said machine through the engagement of said ratchet and said pawl device before and in timed 65 relation with the engagement of said clutch, and means for resetting the parts when said

clutch is disengaged, comprising a manually operable means engageable with said driven member for turning it in a direction opposite to that in which it is driven by said driving member and the ratchet and pawl device to effect resetting of said piston to its initial position through the engagement of said ratchet and said pawl device.

70 9. The combination with a machine of positive driving means including a continuously rotating driving member, a driven member which makes a single turn for a predetermined whole number of machine cycles, an auxiliary starting means for overcoming a part of the starting inertia of the machine, 75 a pawl and a ratchet having the same number of teeth as the cycles of the machine per revolution of said driven member, said pawl and ratchet being interposed between and connected to said auxiliary means and said driven member, and manual resetting means for moving a tooth of said ratchet to a predetermined position with respect to said pawl before starting, the position being that 80 in which in the cycle of the machine there is 85 the lowest starting inertia.

90 10. The combination with a machine of positive driving means including a continuously rotating driving member, a driven member operatively connected to various of the moving parts of said machine, a clutch for operatively connecting said members, a ratchet fixed to said driven member, a pawl device adapted to cooperate therewith, a pneumatic cylinder device connected to and 95 operating said pawl device to move said ratchet to start the machine, a latch to prevent the movement of said pawl device, and means responsive to the movement of said clutch toward its engaged position for tripping said latch, whereby the pneumatic cylinder is permitted to actuate said pawl device to start the machine just prior to the engagement of said clutch tending to relieve the 100 shock and load on the mechanical driving mechanism in starting the machine.

105 11. The combination with a machine of positive driving means including a continuously rotating driving member, a driven member operatively connected to various of the moving parts of said machine, a clutch for operatively connecting said members, a ratchet fixed to said driven member, a pawl device adapted to cooperate therewith, a pneumatic cylinder device connected to and 110 operating said pawl device to move said ratchet to start the machine, a latch to prevent the movement of said pawl device, and adjustable means secured to said latch responsive to a predetermined movement of 115 said clutch toward its engaged position for tripping said latch, whereby the pneumatic cylinder is permitted to actuate said pawl device to start the machine at a predetermined variable interval prior to the engage- 120

125 130

ment of said clutch thus tending to relieve the shock and load on the mechanical driving mechanism in starting the machine.

12. The combination with a machine of
5 positive driving means including a continuously rotating driving member, a driven member operatively connected to various of the moving parts of said machine, a clutch for operatively connecting said members, a
10 ratchet fixed to said driven member, a pawl device adapted to cooperate therewith, a pneumatic cylinder device connected to and operating said pawl device to move said ratchet to start the machine, a latch to prevent the movement of said pawl device, adjustable means secured to said latch responsive to a predetermined movement of said
15 clutch toward its engaged position for tripping said latch, a pneumatic cylinder for moving said clutch toward its engaged position, and a single valve for admitting pressure simultaneously to both said cylinders, whereby said clutch is first moved by its actuating cylinder a predetermined degree toward its engaged position, then said latch is
20 released and the ratchet actuating cylinder is permitted to bring the machine substantially to its full operating speed at which time the clutch is fully engaged and the positive mechanical drive through said clutch continues the movement of the machine parts.

Signed at Hartford, Conn., this 24th day of March, 1928.
